EXERCISE APPARATUS

Robert R. Spackman, Jr., and Marvin E. Johnson, Carbondale, Ill., assignors to Southern Illinois University Foundation, Carbondale, Ill., a corporation of Illinois

Filed July 15, 1963, Ser. No. 75,791

Term of patent 14 years

(Cl. D34—5)

FIG. 1.

FIG. 3.

FIG. 4.

FIG. 1 is a view in perspective of an exercise apparatus embodying our new design;

FIG. 2 is a side elevation of our exercise apparatus as viewed from either side and with the end of a table, to which the apparatus is secured, shown in dotted lines for illustrative purposes only;

FIG. 3 is a top plan view; and

FIG. 4 is a front elevation of FIG. 3.

We claim:

The ornamental design for an exercise apparatus, substantially as shown and described.
